(57) CLAIM

The ornamental design for a lighter, as shown and described.

DESCRIPTION

FIG. 1 is a perspective view of a lighter showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a perspective view thereof showing the cover in an open position; and,

FIG. 9 is a perspective view thereof showing the cutter in an open position with a cigar attached thereto.

The portions shown in broken lines are included for illustrative purpose only and form no part of the claimed design.
